Elliott Fisher Company, New York, N. Y., a cor-
poration of Delaware

Application January 31, 1944, Serial No. 520,558

9 Claims. (Cl. 197—65)

This invention relates to accounting machines and more particularly to a drive mechanism for the travelling carriages of these and like machines.

The invention has for one of its objects to provide a single, impositive drive mechanism for imparting a smooth, constant driving action to the carriage in either working or return direction and operable to automatically increase or decrease the applied power of the drive in accordance with the starting and stopping of the carriage so that ample starting power is assured for overcoming inertia of the carriage when it is released from a rest position and substantially reduced but adequate power is assured for holding the carriage in any of its rest positions.

The increase in weight caused by the present use of longer carriages and the various added equipment thereon has made it especially desirable to provide a drive that is equally efficient throughout the entire run of the carriage in its working direction. Spring drums hitherto used for this purpose have proved unsatisfactory, especially when used with long carriages, because of their diminution in power as the carriage approaches the end of the run.

Use of a number of spring drums does not satisfactorily meet the problem because when their number has been increased to provide sufficient power to insure proper operation of the various carriage controlled parts at the end of the run, the corresponding excessive increase in power at the beginning of the run results in abusive battering of the parts during this period.

Different types of hydraulic drives, substituted for the spring drums, have proved unsatisfactory because of their relatively higher cost coupled with their uncertainty in operation arising from chance of leakage and particularly from variations in the viscosity of fluid correspondent to temperature changes.

The present invention is directed toward providing a drive mechanism that overcomes these objectionable features with a simple, reliably operative, inexpensive structure that is effective to apply a uniform driving power throughout the entire run of the carriage.

Another object of the invention is to provide a carriage drive which operates in such a manner that the speed of the carriage is at all times controlled so that it never accelerates beyond the speed of the driving motor whether the carriage is moving from column to column or making an extended movement by skipping one or more intervening columns.

A further object of the invention is to provide a device of this character with a manually controlled means for permitting manual movement of the carriage when it is desired to use the machine without automatic control.

With these and incidental objects in view, the invention consists in certain novel features of construction and combinations of parts, the essential elements of which are set forth in appended claims, and a preferred embodiment of which is hereinafter described with reference to the drawings which accompany and form part of the specification.

In the drawings—

Fig. 4 is a detailed sectional view of a frictional coupling taken on the line 4—4 of Fig. 3,

Fig. 5 is a view in perspective of the disks employed in the frictional coupling shown in Fig. 4 and

Fig. 6 is a detail view of a manual control of the carriage return mechanism.

GENERAL DESCRIPTION

The invention is disclosed on machines of the type shown in U. S. Patents Nos. 2,023,294, 2,194,270, and 2,216,634, issued to Oscar J. Sundstrand on December 3, 1935, March 19, 1940, and October 1, 1940, respectively, and is an improvement on the drive mechanisms thereof. Only those portions of the machine that have bearing upon the present invention will be herein described in detail, as reference may be had to the foregoing patents for a full disclosure of the Sundstrand machine. The invention can, of course, be applied to any machine having a travelling carriage and is herein shown in connection with a Sundstrand machine for illustrative purposes only.

The machine has the customary movable carriage for supporting paper forms for printing. The carriage is arranged to be controlled for movement in either working or return direction by a shiftable clutch and is stopped in the various columns during the working stroke by the conventional tabulating stops engaging the forward ends of machine operation controlling magazines that are mounted on the carriage control plate.

The invention uses the same motor that is used for cycling the machine to supply the power for driving the carriage on both the working and return strokes. A friction disk coupling is interconnected in the driving train which is connected between the carriage and the motor. Lever connections provided between parts of the tabulating stop mechanism and the coupling are arranged to increase the pressure on the disks of the coupling when the carriage is released by the stops for movement and to decrease the pressure upon the disks when the carriage is arrested by the stops. In this manner there is provided two constants of frictionally applied power, one constant being applied when the carriage is at rest against the stop and being sufficient to hold the carriage securely for printing purposes and the other constant being sufficient to insure ample force to start and move the carriage from arrested position to its next position during working strokes and back to its initial starting position during return strokes. This latter constant of friction is also sufficient to prevent the carriage from overrunning the speed of the motor.

DETAILED DESCRIPTION

Carriage mounting and tabulating mechanism

Referring to Figure 1 of the drawings, there is indicated at 10 a conventional carriage mounted for movement transversely of the machine on antifriction rollers 11 carried in oppositely disposed grooves of a track or bed 12 supported on the machine frame. In its working or tabulating movement the carriage travels toward the observer in Fig. 1, toward the left in Fig. 2. The usual control plate 13 is mounted on the rear of the carriage and carries a plurality of control magazines 14 for automatically controlling the operations of the machine in predetermined columnar positions. The tabulating mechanism is mounted on a plate 15 mounted in the rear end of the machine beneath the forward end of control plate 13. Plate 15 is supported for sliding movement in a direction parallel to the travel of the carriage. This sliding movement is made possible through the provision of slots 16 registering with screws 17 secured in the rear wall 18 of the machine frame. A spring 19 connected to the upper arm of a lever 20 pivoted at 21 tends to move plate 15 toward the right as shown in Fig. 3. The upper arm of the lever carries a stud 22, lying within a recess 23 on plate 15. The lower arm of lever 20 is pivotally connected to a dash pot 24 mounted on the back of wall 18. When the carriage is released for tabulation, spring 19 moves the plate to its right-hand position wherein the left ends of slots 16 are engaged with screws 17 as shown in Fig. 3.

A lever 25 is mounted for vertical movement on a stud 26 secured in plate 15. The right end of lever 25 constitutes a tabulating stop 27 coacting with a companion stop 28 formed upon a slide 29 mounted for vertical movement on plate 15 by means of a screw 30 extending through a slot 31 in slide 29, and by a lever 32 pivoted to slide 29 at 33 and fulcrumed on a stud 34 secured to plate 15. A spring 35 normally holds stop 28 in its lower ineffective position shown in Figs. 2 and 3. A spring 36 tends to hold stop 27 on lever 25 in its upper and right-hand position where a lug 37 on lever 25 rests against a stud 38 on lever 32. As before stated, the carriage is provided with a plurality of magazines 14 (one for each position in which it is desired to have the carriage stop), to coact with the tabulating stops

27 and 28. When the carriage is moved to the left by the drive mechanism later to be described, it brings a magazine 14 against tabulating stop 27. The stop 27 is permitted to slide to the left through the provision of a slot 39, through which stud 26 extends. This tensions spring 36 until the left end of lever 25 strikes an abutment 40.

When the carriage is in its position of rest, one of its magazines 14 rests against tabulating stop 27. When the carriage is to be released for movement from one column to the next, stop 27 is lowered and stop 28 is simultaneously raised. These stops are so positioned that stop 28 is elevated sufficiently to lie in the path of movement of magazines 14 before stop 27 is lowered out of the path of the magazines, so that before the carriage is released for tabulation it moves from its position of contact with stop 27 to a position of contact with stop 28, these stops being slightly offset in the working direction of travel of the carriage. After the stops are so moved, and the magazine 14 has moved into engagement with stop 28, plate 29 is lowered to its original position. This movement releases the carriage to the action of the drive which effects the desired tabulation. Immediately upon the release of the carriage, plate 15 moves to the right under the tension of spring 19. During the tabulation, stop 27 is raised by spring 36 as soon as the magazine passes to the left thereof. This places stop 27 in position to engage the next magazine.

Tabulation of the carriage from one column to another by operation of stops 27 and 28 may be performed automatically by the general operator (not shown) of the machine, or manually by operator of the manual tabulating key (not shown). The slide indicated at 41 corresponds to the slide 685 of Patent No. 2,194,270 and, as shown and described therein, is connected to the general operator of the machine to perform automatic operation of stops 27 and 28. There is indicated at 42 the rear end of a lever that corresponds to the lever 689 of the patent which lever is controlled by the manual tabulation key as fully disclosed therein.

Carriage drive mechanism

The carriage is driven by the same motor that is used for cycling the machine. The motor is indicated at 43. It has a worm 44 (Fig. 2) meshing with a worm 45 encased in a gear housing 46 mounted on the machine frame. A gear 47 connected with worm gear 45 meshes with another gear 48 mounted on the left side of housing 46. Gear 48 meshes with a pinion 49 secured on one end of a shaft 50 journaled in a bearing provided in an upstanding side plate 51 secured to the machine frame and in a bearing provided in housing 46. To the opposite end of shaft 50 there is secured a V-pulley 52 connected by a belt 53 with a second V-pulley 54 formed integral with a cup-shaped housing 55 of a friction disk coupling indicated generally at 56. A spring-urged belt tensioner 53 mounted on plate 51 holds the belt taut about the pulleys. The pulley and housing 54-55 are mounted on a flanged hub 54a (Fig. 4) secured to the left end of a horizontally extending shaft 57 (Fig. 2) journaled in bushings 58 formed on a U-bracket 59 secured to a horizontally extending plate 60 that is secured at 61 to an internal wall of the machine and secured at 62 to an extension 63 formed on gear housing 46. Pulley 54 and hous-

ing 55 are frictionally connected with shaft 57 in a manner to be later described.

A bevel gear 64 secured on the right end of shaft 57 meshes with oppositely disposed corresponding bevel gears 65 and 66 rotatably mounted upon a vertically extending shaft 67. Shaft 67 is journaled at its lower end in a bushing 68 secured on the underside of plate 60 and at its upper end in a bushing 69 secured on a bracket 70 fixed to the machine frame. The shaft is movable for a slight distance vertically in bushings 68-69 and has a collar 72 fixed thereon between gears 65 and 66 by a pin 71. Collar 72 has oppositely disposed dogs 73 and 74 on its upper and lower faces respectively. When shaft 67 is in its lower position, as shown in Fig. 2, dog 73 engages a tooth 75 formed on the upper face of gear 65 so that shaft 67 is rotated in "carriage working stroke" direction. When the shaft is shifted upwardly a slight distance, dog 73 is withdrawn from engagement with tooth 75 and dog 74 is elevated to a position where it engages a tooth 76 formed on the bottom face of gear 66 to reverse the rotation of shaft 67 to "carriage return" direction thus constituting a reversible positive clutch. A collar 77 is secured to shaft 67 above gear 66 by a pin 78 and has upward extensions such as 79 interslidably connected in corresponding recesses 80 provided in a depending hub of a driving pinion 81 supported directly above collar 77 by a bracket 82 (Fig. 1) secured to bracket 70. Sufficient vertical clearance is provided in recess 80 to permit the shifting movement of shaft 67 as just described for the reversible connection and disconnection of the clutch. Pinion 81 meshes with a horizontally disposed rack 83 extending lengthwise and secured to the bottom of the carriage frame, so that as the pinion 81 is rotated in either direction by the connections above described the carriage is driven in a corresponding direction.

The friction coupling 56 (Fig. 4) comprises a series of metal disks 84 of slightly smaller diameter than the interior of cup 55 in which they are mounted. Each of the disks have rectangular openings 86 (Fig. 5) of such size and shape that they fit snugly over the slabbed portions 87 (Fig. 4) formed on the left end of shaft 57. Alternately interposed between disks 84 are a series of disks 88 preferably of fibrous brake lining material or the like. Disks 88 have openings 89a that fit loosely over shaft 57 and radially extending spaced tongues 89 engaging within corresponding slots 90 provided in the periphery of cup 55. A rounded button 91 slidably mounted for axial movement on a reduced end 92 of shaft 57 caps the assembly and has its inner face bearing against the outer face of the outermost disk 84, the cup being held in position by a lever 93 later to be described.

Disks 84 are preferably formed slightly "off the flat," i. e., they are formed so that their surfaces are slightly irregularly distorted with respect to the surfaces of disks 88, so that when they are held together as later described, there is provided a slight yielding pressure between the surfaces of disks 84-88.

Coupling control mechanism

The mechanism for controlling the degree of frictional contact between the surfaces of plates 84-88 is under the control of the tabulating mechanism.

This mechanism includes a lever 93 pivoted at 94 on a flange 95 formed on an auxiliary side

plate 96. Plate 96 is secured in spaced relation to plate 51 by spacing sleeves and tie bolts 97. The rear end of lever 93 is pivoted at 98 (Fig. 3) to one end of a horizontally extending link 99. The opposite end of link 99 is guided for sliding movement by a pin-and-slot connection 100 with lever 20. A shoulder 101 on the right end of link 99 abuts a stud 102 secured in lever 20 below its pivotal center 21. The parts are so proportioned that when a magazine 14 engages tabulating stops 27-28 and moves plate 15 toward the left as shown in Fig. 1, the distortion of disks 84 causes the disks to move apart slightly one from the other with button 91 pressing against the forward end 103 of lever 93.

In this condition sufficient portions of the engaging surfaces of the disks remain frictionally engaged to cause gear 81 to be rotated through shafts 57 and 67 with a smooth and adequate power to hold the engaged magazine 14 constantly against the stop 27 to thus secure a firm holding action upon the carriage for printing purposes.

Upon release of the carriage for movement to the next columnar position, immediate the lowering of stop 27 as previously described, plate 15 moves to the right as lever 20 swings clockwise about its pivot 21 under the influence of spring 19. This moves stud 102 clockwise and thrusts link 99 leftwardly to increase the pressure of the forward end 103 of lever 93 upon button 91 to intensify the frictional pressure contact between the surfaces of disks 84-88, whereupon an ample and smooth driving power is imparted through the shafts and gearing to start and constantly move the carriage from its inert position of rest to the next columnar position. Upon the next magazine 14 engaging stop 27, stud 102 is again swung slightly counterclockwise away from shoulder 102 releasing the pressure lever 93 so that the coupling 56 again imparts a reduced but adequate driving power to hold the carriage in this rest position, and so on.

Since the full pressure of lever 93 is upon coupling 56 whenever the carriage is moving, a sufficient frictional engagement is maintained between disks 84-88 to insure against the carriage accelerating through momentum beyond the speed of the driving motor 43.

Carriage return

The carriage return mechanism is similar to that disclosed in the before-mentioned Patent No. 2,194,270 and hence will be herein only briefly described. It includes the usual carriage return block 104, located on the under side of the carriage to the right of the last columnar magazine 14. As the carriage completes its working stroke following its last stop, block 104 engages one arm 105 of a three-armed bell crank 106 pivoted at 107 in the machine frame. A flanged arm 108 of the bell crank lines within an annular groove in collar 77. As block 104 strikes arm 105, bell crank 106 rotates counterclockwise to shift collar 77 and 72 upwardly, so that dog 74 of collar 72 engages with tooth 76 of gear 66 as dog 73 is withdrawn from engagement with tooth 75. Since gear 66 rotates in an opposite direction to gear 65, return movement of the carriage is effected through the reverse driving action of gear 81.

Toward the end of the return stroke a block 124 engages arm 105 of bell crank 106 from a direction opposite to that in which it was engaged by block 104 and rotates the bell crank clockwise to restore the clutch into tabulating engagement with gear 65. The usual spring-urged detent 109

engages a third arm 110 of bell crank 106 to hold the bell crank in either of its moved positions.

A manual carriage return control, identical with that disclosed in the before-mentioned Patent No. 2,194,270, is provided in this machine and comprises a lever 111 (Fig. 6) pivoted at 112 in the machine frame. The rear end of the lever has an upturned portion 113 resting directly beneath a peripheral flange 114 provided on collar 72. Depression of the key causes collar 72 and shaft 67 to be raised in exactly the same manner as previously described in connection with carriage control of the return movement.

It will be noted that, since plate 15 occupies its rightward position as shown in Fig. 3 during the entire return movement, full pressure is applied by lever 93 upon button 91 of the friction coupling 56 so that the higher constant of frictionally applied power is effective during the entire return movement.

Manual control

Machines of this type are equipped with a key known as the normalizer or manual control key which, when depressed, eliminates machine operation of the carriage tabulating stops and control of various machine functions by the carriage. When the machine is used with this key depressed, such as for printing items and totals one below the other in a single column, it may be desirable to manually shift the carriage laterally from one column to another. To facilitate this movement it is necessary to release the tension of spring 19 upon lever 93 and button 91 so that there is the relatively lighter frictional pressure applied to the disks 84-88 during such operations. The manual control or normalizing key is herein indicated in Fig. 3 at 115 and corresponds to key 870 in Patent No. 2,194,270.

The key is mounted for vertical sliding movement and is provided with a bayonet slot 116 engageable with a mounting stud 117 for holding the key locked in depressed position. A lever 118 pivoted at 119 is connected at its forward end by a pin-and-slot connection 120 with key 115. The rear end of this lever lies beneath one arm of a bell crank 121 pivoted at 122 in the machine frame. The opposite arm of the bell crank has a flange 123 which, when key 115 is in its raised or ineffective position and plate 15 is in its rightward position as shown in Fig. 3, abuts the right end of the plate. Upon depression of key 115, bell crank 121 is rocked counterclockwise to thrust plate 15 toward the left against the tension of spring 19 and to hold the plate in such position as long as key 115 remains latched. This removes the full pressure of lever 93 against button 91 and thereby lightens the frictional contact between disks 88-84 as previously described. Hence, when the machine is being manually operated, the carriage may be moved manually from column to column, sufficient force being applied thereto to overcome the opposition of the frictional coupling 56. As before stated, the power applied by the frictional coupling when the parts are in this position is sufficient to firmly hold the carriage against tabulating stop 27 for printing purposes.

While the form of mechanism herein shown and described is admirably adapted to fulfill the objects primarily stated it is to be understood that it is not intended to confine the invention to the one form of embodiment herein disclosed for it is susceptible of embodiment in various forms

all coming within the scope of the claims which follow.

We claim:

- 5 1. In a machine of the class described having a travelling carriage and releasable means for holding the carriage from movement in one direction, the combination of a motor, drive mechanism including an impositive coupling connected between said motor and said carriage for driving said carriage in said one direction, and means controlled by the releasable holding means for decreasing the positiveness of the coupling when the carriage is held by said means and increasing the positiveness of the coupling when the carriage is released by said means.
- 10 2. In a machine of the class described having a travelling carriage and releasable means for holding the carriage from movement in one direction, the combination of a motor, an impositive coupling and a positive reversible clutch interactively connected between said motor and said carriage and operable to drive the carriage in said one direction or in an opposite direction, and means controlled by the carriage holding means for decreasing the positiveness of the coupling when the carriage is engaged by the holding means and increasing the positiveness of the coupling when the carriage is released from the holding means.
- 15 3. In a machine of the class described having a travelling carriage and releasable means for holding the carriage from movement in one direction, the combination of a motor, a drive mechanism comprising a unitary system of impositive and positive interconnected driving connections connected between the motor and the carriage and capable of driving the carriage in said one direction or in an opposite direction, and means cooperating between the carriage holding means and the impositive connection for increasing the intensity of said connection when the holding means releases the carriage for movement and decreasing the intensity of said connection when the carriage is stopped by the holding means.
- 20 4. In a machine of the class described having a travelling carriage, a motor, a drive between the motor and the carriage including a friction coupling and a positive clutch, the clutch being operable to reverse the direction of drive for moving the carriage in either working or return direction and the coupling being operable to modify the intensity of the drive, releasable means for arresting movement of the carriage in working direction, and means under the control of the releasable means and cooperating with the coupling to modify the degree of frictionally applied power conformably to the stopping and releasing of the carriage.
- 25 5. In a machine of the class described, the combination of a movable paper carriage, a motor, a constantly driven connection between the motor and the carriage, said connection including a clutch shiftable to reverse the movement of the carriage from working to return direction and vice versa, a releasable member engageable by the carriage during its movement in working direction, and a connection between the releasable member and the impositively driven connection for decreasing the intensity of said connection when the carriage engages the member and increasing the intensity of said connection when the carriage is released by said member.
- 30 6. A drive for travelling paper carriages comprising a motor, a clutch shiftable to drive the carriage in working or return directions, releas-

able means for stopping the carriage in the working direction movement, a constantly acting impositive drive connection between the motor and the clutch and means under the control of the releasable stop means cooperating with the impositive connection for decreasing the intensity of the drive when the carriage is stopped by said releasable stop means.

7. In a machine of the class described, having a travelling carriage, a friction disk coupling, a reversible positive clutch, said coupling and said clutch being interoperatively connected between the motor and the carriage to drive the carriage in either a working or return direction, means for releasably stopping the carriage in its movement in working direction, and means including connections between the releasable stop means and the coupling for imparting variable pressure upon the disks of the coupling so that reduced but sufficient power is applied through the coupling to hold carriage against the stop means when the carriage is arrested and substantially increased power sufficient to overcome the inertia of the carriage is applied through the coupling when the carriage is released by the stop means.

8. In a machine of the class described having a travelling carriage and releasable stop means for

holding the carriage from movement in one direction, a motor, drive mechanism including an impositive coupling connected between the motor and the carriage, and means connected between the releasable stop means and the coupling operable to increase and decrease the application of power through the coupling to the carriage in correspondence with the releasing and stopping of the carriage by the releasable stop means.

9. In a machine of the class described having a travelling carriage, and releasable stop means for holding the carriage from movement in one direction, a manipulative member, a motor, drive mechanism including an impositive coupling connected between the motor and the carriage, means connected between the releasable stop means and the coupling operable to increase and decrease the application of power through the coupling to the carriage in correspondence with the releasing and stopping of the carriage by the releasable stop means, and means under the control of the manipulative member for preventing operation of the connecting means to increase the application of power through the coupling even though the carriage is released.

OSCAR J. SUNDSTRAND.
